PANELS FOR FLEXIBLE CARDS

Carl F. Wolters, New Canaan, and Robert W. Riggs, Old Greenwich, Conn., assignors to Sperry Rand Corporation, New York, N. Y., a corporation of Delaware

Application October 20, 1955, Serial No. 541,564

3 Claims. (Cl. 129—16)

This invention relates to new and useful improvements in the structure of panels for flexible cards, and has particular reference to novel means for readily applying runways to and removing the runways from said panels.

In panels of the general type wherein a series of runways are mounted on a base board and receive a series of flexible cards in overlapping relation thereon it becomes important to provide means whereby the runways can be quickly and easily and accurately mounted on the panel board and quite as easily removed when desired. A main object of the invention is to provide a structure by which these aims may be achieved.

Furthermore, it is also important that the structure of the runway mounting be such as to readily permit one runway to be associated with another while that other is on the board so that cards may be shifted from one runway to the other without the use of extra and separate transfer mechanism. A further object of the invention is to achieve this aim as well.

A still further object is to provide a structure which achieves the above results and which is simple in construction and operation and economical to manufacture and requires no major alteration of the panel boards and runways now in use.

Generally speaking, the invention includes a panel board on which is disposed a lock slide member and a card-supporting runway disposed on the board over the lock slide with means on the board and the runway to interengage and accurately position the runway on the board. The lock slide is movably mounted on the board and has a locking and an unlocking position with respect to the runway. Means are provided on the runway and the slide to cooperate to lock the runway to the board when the slide is in locking position and to permit the removal of the runway from the board when the slide is in unlocking position.

More particularly the construction resides in the interengagement of certain openings such as slots and notches on the runway with studs on the board to aline the runway in proper position. It also concerns the provision of a keyhole slot on the runway to be operatively engaged with and disengaged from a stud on the lock slide so that the runway may be attached to and removed from the board by sliding the lock slide in one or another direction.

Still more particularly the invention concerns the provision of means on the lower end of one runway which cooperates with means on the upper end of another runway to permit the runways to be easily and quickly alined so as to facilitate the transfer of cards from one runway to another without the use of separate transfer mechanism.

The present preferred form which the invention may assume is shown in the drawings, of which,

Fig. 1 is a broken plan view of a panel board with the card runway in position thereon but with the lock slide is unlocked position;

Fig. 2 is a plan view of a panel with a runway shown supporting cards and showing means for transferring cards to another runway;

2

Fig. 3 is a longitudinal section taken on the line 3—3 of Fig. 1;

Fig. 4 is a longitudinal section taken on the line 4—4 of Fig. 1;

5 Fig. 5 is a longitudinal section taken on the line 5—5 of Fig. 1; and,

Fig. 6 is a cross section taken on the line 6—6 of Fig. 1.

Referring now to the specific form of the invention illustrated herein it will be seen that there is a panel board 10 on which are to be disposed, in spaced parallel relation, a series of runways 11, of elongate shape and having oppositely disposed flanges 12 and a central longitudinal raised channel portion 13. As thus far disclosed these runways are of the usual form to receive overlapping cards

15 14 of the flexible type to be interlocked with the flanges 12 as is well known. On top of the channel portion 13 are disposed spaced key-hole slots 15. At the bottom edge of the runway 11 on opposite sides of the channel 13 are notches 16 adapted to bear against the shoulder portions 20 of headed studs 17 mounted on the panel board 10. The top edge of the runway 11 is adapted to lie against abutments 18 when the runway is disposed as shown in Fig. 1. These abutments are mounted on the panel board 10.

In order to facilitate the attachment to and removal 25 from the panel board 10 of the runway 11 a lock slide is employed. This lock slide is in the form of a slide plate 19 which is disposed to slide along the panel board 10 within the confines of the side edges of the channel 13 as clearly shown in Fig. 1. It is provided with regular spaced 30 slots 20 which receive headed studs 21 mounted on the panel board 10. The lock slide 19 has a headed stud 22 thereon which is adapted to be received in the upper key-hole slot 15 on the runway. The upper end of the lock slide 19 has an outwardly turned flange 23 to enable 35 the finger of the operator to move the slide up and down. The upper edge of the runway 11 is also provided with spaced notches similar to the notches 16 at the bottom, above mentioned. In Fig. 1 the slide 19 is shown in its upward or unlocking position.

40 When a runway 11 is to be applied to the panel board, the lock slide 19 is moved upward to the position shown in Fig. 1. Then the runway is brought to the board so that first the lower edges thereof will cause the engagement of the notches 16 therein with the studs 17. Then 45 the runway is swung flat against the board 10 and the stud 22 on the lock slide 19 will enter the center of the upper key-hole slot 15 as shown in Fig. 1. At this time the upper edge of the runway 11 will lie in contact with the abutments 18. When the runway is thus disposed, the 50 headed stud 22 lies in the center of the upper key-hole slot 15 and a fixed stud 24 on the panel board 10 lies in the upper end of the lower key-hole slot 15. This stud 24 therefore also enables the runway to be accurately positioned. The lock slide 19 is then moved down to seat the 55 headed stud 22 in the upper narrow end of the upper key-hole slot and in this position the runway is securely held in close relation flat against the panel board. To remove the runway, the slide is moved upward whereupon the runway can be lifted readily from the board.

60 Another feature of the invention has to do with the notches 16 at the upper and lower edges of the runways 11. When it is desired to transfer cards 14 from one runway to another, the two runways are disposed as shown in the lower part of Fig. 2 where the notches at the lower edge 65 of the upper runway engage the studs 17 and the notches at the upper edge of the adjacent runway also engage said studs. While the two runways are held in this relation, manually or otherwise, the cards 14 may be easily and readily slid from one runway to the other, without the use of any particular transfer mechanism.

70 While I have described what I consider to be a highly desirable embodiment of my invention, it is obvious that

many changes in form could be made without departing from the invention, and I, therefore, do not limit myself to the exact form herein shown and described, nor to anything less than the whole of my invention, as hereinbefore set forth, and as hereinafter claimed.

What we claim is:

1. In combination, a panel board, a card runway disposed on the board and extending between the top and bottom edges of the board, said runway having oppositely disposed flanges and a central longitudinally raised channel portion with a key hole slot intermediate its length, means fixed on the board and abutting the top and bottom edges of the runway when the runway is in position thereon to prevent longitudinal movement of the runway thereon, a slideable lock plate disposed on the panel board within the confines of the side edges of the channel portion of the runway, said lock plate having spaced straight slots therein, headed studs fixed on the board and projecting through said last named slots to guide and limit the reciprocal movement of the lock plate on the panel.

board, a headed stud on the lock plate and cooperating with the key hole slot on the channel portion to hold the runway to the board or permit its ready removal therefrom dependent upon the position of the lock plate.

2. The invention of claim 1 in which the runway at its lower edge is provided with spaced notches, and the fixed abutting means at the lower edge of the runway comprises headed studs the stems of which lie in said notches.

3. The invention of claim 2 in which the fixed abutting means at the top of the board are fixed studs bearing against the top edge of the runway.
